UNITED STATES PATENT OFFICE.

CHARLES W. UNDERWOOD, OF CROWLEY, LOUISIANA.

CAR-DOOR LOCK.

1,171,989.

Specification of Letters Patent. Patented Feb. 15, 1916.

Application filed August 16, 1915. Serial No. 45,771.

To all whom it may concern:

Be it known that I, CHARLES W. UNDERWOOD, a citizen of the United States, residing at Crowley, in the parish of Acadia and State of Louisiana, have invented certain new and useful Improvements in Car-Door Locks, of which the following is a specification, reference being had to the accompanying drawings.

10 My invention relates to doors, and particularly to the doors of cars, and the primary object of my invention is the provision of a means for forcing a car door inward toward the side wall of the car and holding it in a locked position, thus preventing leakage of water or the inlet of snow into the car through the joint between the car door and the car.

20 A further object of my invention is to provide a car door which is held at four or more points of contact when in a locked position, thus preventing the warping or springing of the door under any and all conditions, thus insuring at all times a perfectly operating 25 door which will last as long as any other part of the car.

30 A further object of my invention is to provide means whereby a constant strain or tension is applied to the door when it is closed and sealed, making the door absolutely weather-proof at all times and preventing any tendency of the car door to spring outward or warp.

35 A further object of my invention is to provide a locking mechanism which is mounted on the door itself and which is so constructed that it is possible to operate and lock the car door even if the car door is hanging out of plumb with the door opening.

40 A further object of my invention is to provide a construction wherein clamp hooks are mounted upon the door adapted to engage with anchoring bolts or like devices on the door frame and with resilient cross bars 45 upon which the clamp hooks are mounted, so constructed that the tension or resilience of the cross bars will constantly apply pressure to the car door thus taking up any wear that may take place and insuring a water-tight joint.

Other objects will appear in the course of the following description.

My invention is illustrated in the accompanying drawings, wherein:

Figure 1 is a fragmentary elevation of a 55 portion of a railway car with my improved door locking device applied thereto, the door being broken away; Fig. 2 is a longitudinal sectional view on the line 2—2 of Fig. 1, showing the door in its locked position; Fig. 60 3 is a like view to Fig. 2, showing the door in its unlocked position; Fig. 4 is a fragmentary perspective view of one edge of the door and a portion of the adjacent frame; Fig. 5 is a detail sectional view of the locking lever 26 and the means for locking the lever in position; Fig. 6 is a face view of a portion of a door frame showing a different form of anchoring device; Fig. 7 is a section 65 on the line 7—7 of Fig. 6; Fig. 8 is an enlarged face view of the sector 30.

In Figs. 1 to 5, 2 designates a car of any suitable construction, shown as having a door opening 3 defined by the upper and lower sills 4 and 5 and by the vertical studding 6. The car door 7 is of any suitable construction and as illustrated is mounted in the usual way to slide to an open or closed position. To this end the car door 7 at its upper end is provided with a hanger 8 which carries rollers 9 engaging with the rail 10. This is no part of my invention and I do not wish to be limited to any particular means thereto for mounting the door for sliding movement. The car door is 80 shown as prevented from outward movement at its lower end by the hooks 11.

85 In the form of construction shown in Figs. 1 to 5, anchoring bolts 12 pass through the studding 6 and extend laterally therefrom parallel to the plane of the door and the side wall of the car. These anchor bolts may be of any suitable form. The door 7 is provided with a plurality of transversely extending rotatable cross bars 13 which 90 have the form of shafts, each cross bar being formed at its middle with a cranked portion 14 whose details of construction will be later described. The extremities of each cross bar 13 extend beyond the side edges of the 95 100

door and are there provided with the clamping hooks 15 which are rigidly attached to the cross bars 13. The ends of each cross bar 13 are supported in guide brackets each comprising a base 16 and an elliptical or oval bearing 17. The longitudinal axis of this ellipse extends upward and outward in divergent relation to the face of the door as illustrated in Fig. 2. The width of the ellipse is practically the same as the diameter of the shaft or cross bar 13. The upper end of each elliptical guide is formed with an outwardly or laterally projecting arcuate lug 18 forming a stop and disposed in the plane of the hook 15. The base of each hook 15 is formed with an inwardly projecting pointed lug 19. It is to be understood that the hooks 15 are adapted to engage the anchoring bolts 12 when the door is in its closed position, and for the purpose of rotating these clamping hooks into or out of engagement with the anchoring bolts and placing a strain upon the cross bars 13, I provide means for rotating the shafts or cross bars 13 and at the same time raising or lowering these cross bars. This means, as illustrated, comprises a vertically reciprocatable bar 20 which may or may not be mounted in suitable guides 21 as desired. The upper and lower ends of this bar are provided with the eyes 22 which engage the cranked portions 14 of the shafts or cross bars 13. Intermediate the length of the bar 20 there is provided a pin or bolt 23 whose outer end is supported by a strap 24, and this pin or bolt 23 engages in a slot 25 formed in the extremity of an arm 26 of an angular lever designated generally 27. This lever is pivoted at 28 upon the face of the car door and has a downwardly depending arm 29 forming a handle whereby the lever may be moved. This arm 29 passes beneath a sector 30 which is attached to the car door and spaced therefrom, and the arm 29 is guided properly upon this sector by means of the outwardly projecting eye or perforated lug 31. The lower extremity of the arm 29 is formed with a handle 32 whereby the lever may be readily manipulated. The sector is provided with a longitudinally extending rib 33 terminating short of the end of the sector. The inside face of the sector is provided with an arcuate lip 34 also terminating short of the ends of the sector to provide two sockets 35 and 36. Disposed upon the face of the sector opposite the socket 36 is a locking pin seat 37. Slidably mounted upon the arm 29 is a collar 38 carrying upon it and formed with it the locking pin 39 and having the hook-shaped head 40. This pin 39 is longitudinally slotted as at 41. When the handle 29 is shifted in one direction, that is, over toward the seat 36, the door will be locked

and it may be held in this locked position 65 by shifting the collar 38 along the handle so as to carry the locking pin into engagement with the seat 37, and the collar into engagement with the seat 36. When the handle is shifted in the reverse direction 70 the door is unlocked and the locking devices may be held in their unlocked position by shifting the collar 38 into the seat 35. The pin 39 of course passes through the perforated lug or eye 31 and a padlock or other suitable device is adapted to be engaged with the slot 41 and lock this pin from accidental removal. 75

The operation of my locking device is as follows: Assuming that the door is in its closed position, but the bar 20 is shifted downward to its lowest position and the hooks 15 are retracted, then upon a movement of the handle 29 to the right in Fig. 1, the bar 20 will be raised. This raising 80 of the bar first acts to rotate the shafts or cross bars 13, thus throwing the hooks into engagement with the anchoring bolts. A further upward movement of the bar 20 acts to lift the bars or shafts 13 and as they 85 are lifted the ends of the bars or shafts ride outward in the elliptical bearing 17 thus straining the bars 13. The resilience of these bars or shafts 13 is such that the bars or shafts will give after the hooks have 90 been brought to their fully locked position, and when the pin 39 is in engagement with the pin seat 37 these bars 13 will be drawn upward at the middle and placed under tension, thus resiliently drawing the door against 95 the face of the door frame. When it is desired to unlock the door the handle 29 is shifted reversely or toward the left in Fig. 1, which causes the bar 20 to shift downward. This first acts to relieve the strain 100 on the bars 13 by carrying the bars downward in the elliptical bearing 17 and then acts to rotate the bars 13 so as to carry the hooks out of engagement with the anchoring bolts. When the hooks are fully re- 105 tracted they will engage with stop lugs 18 as illustrated in Fig. 3. The door may be then readily shifted away from the door opening in the usual manner.

While I do not wish to be limited to any particular way of constructing the shafts or cross bars 13, I have illustrated the cranks as being formed by castings having socketed ends within which the extremities of the sections forming the cross bars 13 110 are inserted and to which they are attached in any suitable manner as by key pins or the like.

While in Fig. 1, I show a car construction which requires that the locking bolts 12 shall be disposed in the studdings 6 and project laterally therefrom, yet there are other forms of car construction where these

anchoring bolts in the form illustrated in Fig. 1 cannot be applied. Thus in Fig. 6 I show a form of car wherein the sheathing of the car, designated 42, covers the framework of the car entirely. Under these circumstances I form the stud or upright 43 behind the sheathing with a seat 44 and also form a seat in the sheathing 42. In this seat I dispose the anchor plate 45 which 5 anchor plate has a head formed with a depression or recess 46 and with a cross bar 47. The head of this anchoring device is formed integral with the bolt shank 48 which extends into and through the stud- 10 ding 43 and is engaged by a nut, this nut being preferably countersunk in the stud- ding. Otherwise than this the construction is precisely the same as previously de- 15 scribed. The hooks 15 instead of engaging with anchoring bolts, as at 12, engage with the cross bars 47. It will thus be seen that the cross bars 47 and the studs or bolts 12 are the equivalents of each other and per- 20 form the same function.

25 The locking device heretofore described will at all times hold the door tightly en- gaged with the face of the door frame and will at all times place a strain upon the door which will hold it closed and prevent 30 the inlet of rain, snow or dust. It will be seen that the door is braced by a plurality of transversely extending cross bars and that thus the door is forced inward at a plural- 35 ity of points. It will also be seen that when strain is placed upon these cross bars 13 the middle of the door is forced inward as well as the side margins of the door. Thus the door is held from warping. Furthermore, the strain placed upon the door is distrib- 40 uted not only by the cross bars but by the bar 20. While I have illustrated two cross bars it will of course be understood that more cross bars might be used if desired. The resilient cross bars take up any wear 45 that may take place in years of use and pre- vent the door from warping or from spring- 50 ing, and by my mechanism it is possible to lock the door even though the door is hanging out of plumb with the door open- 55 ing in the car by reason of the fact that the cross bars have a certain amount of play in the vertically disposed slots of the bearing members.

My invention very greatly increases the 55 life of the door relative to the car. At present the life of a car door is relatively short. The shifting of the load, the use of pinch bars, and the nailing of cleats causes the door to shut and open with difficulty and 60 the result is that the door is constantly subjected to very rough handling. With my construction there is no necessity of cleats, no necessity of using pinch bars for the purpose of opening the door, and the pres-

sure of the goods against the inside of the 65 door is resisted by the resilient shafts or cross bars 13.

Having thus described my invention, what I claim is:

1. The combination with a door frame 70 and a door, of members mounted on the door and adapted to have operative engage- ment with the door frame and being mount- ed for vertical movement relative to the door, and means for flexing said members 75 and thereby placing them under tension upon a vertical movement.

2. The combination with a door frame and a door, of a plurality of transversely extending rotatable bars rotatably mounted 80 upon the face of the door and projecting beyond it, hooks mounted on each end of said bars and adapted to operatively engage the door frame, upwardly and outwardly inclined walls with which the ends of the 85 bars engage, and means for simultaneously rotating said bars and shifting them verti- cally upward into wedging engagement with said walls.

3. The combination with a wall having a 90 door opening, of a sliding door mounted thereon for movement into position within said opening, a plurality of transversely ex- tending bars rotatably mounted upon the 95 face of the door and projecting therebe- yond, each of said bars being formed with a cranked portion at its middle, radially disposed hooks mounted upon the ends of each bar, members mounted upon the wall 100 with which the hooks are adapted to engage 105 when the door is in place, brackets mounted adjacent the side margins of the door and each having an outwardly extending web formed with an elongated upwardly and outwardly extending slot through which the 110 corresponding end of the bar passes, a ver- 115 tically movable member mounted upon the face of the door for sliding movement and having operative engagement with the cranked portions of said bars, and means for shifting said member upward to thereby rotate the bars and shifting them vertically to thereby cause the walls of said slots to force the outer ends of the bars outward away from the face of the door.

4. The combination with a wall having a 120 door opening, of a door mounted for move- ment into position within said opening, a transversely extending bar rotatably mount- ed upon the door and projecting therebe- yond, hooks carried by the bar, members carried by the wall with which the hooks 125 are adapted to engage when the door is in place, brackets mounted adjacent the side margins of the door and having an elongated upwardly and outwardly extending slot through which the corresponding ends of the bar passes, and a movable member

mounted upon the door and having operative engagement with the shaft and adapted to rotate the bar and shift the same vertically to thereby cause the walls of the slot to force the outer ends of the bars outward away from the face of the door.

In testimony whereof I hereunto affix my signature in the presence of two witnesses.

CHARLES W. UNDERWOOD.
